UNITED STATES PATENT OFFICE.

FITZALLAN B. WILLIAMS, OF CHICAGO, ILLINOIS.

FOLDING OR WARDROBE BEDSTEAD.

SPECIFICATION forming part of Letters Patent No. 376,127, dated January 10, 1888.

Application filed March 26, 1887. Serial No. 232,459. (No model.)

To all whom it may concern:

Be it known that I, FITZALLAN B. WILLIAMS, of Chicago, Illinois, have invented certain new and useful Improvements in Folding 5 or Wardrobe Bedsteads, of which the following is a specification:

The invention relates to improvements in folding or wardrobe bedsteads in which a counterpoise is employed to assist in the opening and closing of the bed; and the objects of 10 the improvements are, first, to provide improved means for causing the pivot or fulcrum on which the folding frame rests to shift toward the head-board during the operation of 15 raising the folding frame from a horizontal to a vertical position and from the same during the operation of lowering the folding frame from a vertical to a horizontal position, and, second, to provide improved means for supporting the counterpoise and connecting it 20 with the upright frame and sliding head board in such manner as to require comparatively small weight to balance the folding frame. I attain these objects by the mechanism illustrated in the accompanying drawings, of 25 which—

Figure 1 is a side elevation of a wardrobe-bedstead containing the invention, the folding frame being let down to a horizontal position. 30 Fig. 2 is a side elevation of the same with the folding frame in a vertical position. Fig. 3 is a rear view of the bed with the folding frame in the same position as shown in Fig. 2. Figs. 4 and 5 are details.

A designates the stationary or upright frame, and B the folding or swinging frame, both of which may be of the ordinary construction. The upright frame is provided with rear cross-pieces, a , at the top and bottom, and also a 40 similar cross-piece in front, at a' , to hold the base together in front in the usual manner. The head-board B' is fitted into grooves in the inner faces of the uprights, near the rear edge thereof, so as to slide up and down therein 45 freely. These grooves may be readily formed by fastening a couple of cleats, as a^2 , upon each side a little distance apart, so that the head-board or metal T-heads, as a^3 in dotted lines, set in the edge thereof at the bottom and 50 top may project into the space between and slide up and down therein. The upper edge of the head end of the swinging or folding

frame is hinged to the bottom of the head-board in the ordinary way, so that as it is let down to a horizontal position the head-board 55 will thereby be raised, and as it is raised to a vertical position the head-board will be lowered to the position in which it is seen in Fig. 3.

The pivots on which the folding frame is 60 supported consist of two pins or trunnions, b , one upon each of the side rails, and project outward. The trunnions may be secured in any convenient way; but I prefer to form them on a plate, b' , provided with screw-holes for 65 attaching them to the side rails.

The trunnions are of sufficient length, so that by making holes through the side rails adapted to receive them the plates may be applied and secured on the inside of the rails, 70 and they will project through the proper distance beyond the outer surface of the rails to engage in seats provided in the supports. These supports consist of swinging trunnion plates or bars E, secured, one on each side, to 75 the stationary or upright frame by means of two links, $e e'$, one of which, e , is pivoted to the base of the upright below the plate and likewise pivoted to the front end thereof at e^2 , so as to support it from below, and the other, 80 e' , is pivoted at its top to the upright above the plate, and has its lower end likewise connected to the rear end of the plate E at e^3 , so as to support it from above. I prefer to make the lower links the heavier and place the trunnion-seats e^4 near to the front ends of the plates, so that the lower links will sustain the 85 greater part of the weight of the folding frame.

By such link-connection of the trunnion-plates with the upright frame said plates are 90 permitted to swing toward and from the head-board during the operation of closing and opening the bed, so as to allow the head-board to slide up and down in its groove without lateral movement, tending to cause it to bind in 95 the groove. The connection of the links so as to support the trunnion-plates from below at one end and from above at the other, the points of support of the links being in different vertical planes and the links passing their vertical centers at different times, affords the 100 same ease of motion to the plates at all points throughout their limit of movement. I have found that the trunnion-plates thus supported

afford a shifting of the fulcrum in operation which is superior both in extent and ease of movement to anything that has yet come under my observation.

5 The plates *b'*, provided with trunnions *b* and screw-holes to adapt them to be fastened to the side rails, and the swinging trunnion-plates *E*, having links *e e'*, pivotally connected and provided with a socket, *e'*, for the trunnions, are designed to be made and sold in sets consisting of two of said plates *b'* and two of the trunnion-plates, adapted to be attached to any wardrobe-bedstead of the class mentioned.

15 I am aware that the patent, No. 349,643, of September 21, 1886, to Gould and Cook, shows a folding bed having two links on each side, pivoted at one end to the upright frame and at the other to the folding frame, one of such links extending upward from the point of its connection with the folding frame and the other downward from its point of connection with said frame. Such is not my invention, not only because the trunnion-plates are wanting, but because the operation is different.

25 By supporting the folding frame on a single trunnion or pivot on each side resting on a swinging trunnion plate, as by my construction, the amount of its movement toward and from the back of the upright frame is not fixed or positive, but adapted to the position of the weight or head-board. The front end of the folding frame, when the bed is closed or opened, will not describe an arc, but by the swinging 35 of the plates more or less will follow the vertical plane in which the weight is made to move, whereas by the prior construction the amount of the movement is necessarily fixed and governed by the links themselves, and if 40 a counterpoise-weight were connected to the head end of the folding frame it would necessarily move in an arc in operation.

The weight is placed in a weight-holder, *F*, which is suspended by bars *f* to the ends of 45 two levers, *G*, which are connected at *f'* to the top of an upright piece, *F'*, bolted to the rear side of the sliding head-board, so as to support said levers. To the top ends of these 50 levers are pivoted two links, *G' G'*, pivotally connected at their upper ends to the cross-piece *a* of the upright frame, said links and levers forming a pair of lazy-tongs, whereby the weight will be raised as the sliding head-board rises through greater distance than the 55 distance said head-board moves.

A system of levers forming lazy-tongs for raising the weight is shown, and in a prior application for a patent for wardrobe-bed-

steads, Serial No. 210,400, filed by me August 9, 1886, six levers are used and the links *6c* by which the weight is suspended have their upper ends attached to the lower pair of levers at or near their longitudinal center, and their lower ends are attached directly to the weight; but in my present invention only four 65 levers are used, and the suspending links or bars *f* are attached to the extreme ends of the lower pair of levers and provided with hooks at their lower ends adapted to engage eyes in the weight-holder *F*, so as to be disengaged 70 therefrom.

The weight-holder is a receptacle into which one or more bars of weight may be placed in order to vary the weight, and thus adapt the amount thereof to different requirements. 75 The construction is thus simplified and made lighter and at less cost, and the weight is made readily detachable. The purpose here is to cover the improvement merely, and not the broader invention, as shown in my said prior 80 application.

What I claim is—

1. The combination, with the upright and folding frames, of swinging trunnion-plates *E*, said plates being supported on the upright 85 frame by being connected thereto, at opposite points on the inside, at their front ends by pivotal links, as *e*, supporting them from below, and at their rear ends by pivotal links, as *e'*, supporting them from above, being thus 90 adapted to engage the trunnions of the folding frame and afford them a free movement toward and from the back of the upright frame, substantially as specified.

2. A set of irons for a wardrobe-bedstead, 95 said irons consisting of two trunnion-plates, *E*, provided with pivotal links *e e'* and trunnion-sockets *e'*, and two plates, *b'*, each provided with screw-holes at the ends and a trunnion, *b*, in the center, substantially as specified. 100

3. As an improvement in wardrobe-bedsteads, the combination, with the weight-holder *F*, which consists of a receptacle provided with eyes at or near each end, of the rods *f*, having hooks formed on their lower 105 ends, and the lazy-tongs formed of levers *G G'* and *G' G'*, said rods *f* being pivoted to the lower ends of levers *G*, said levers *G* being pivoted to support *F'* on the sliding head-board, and said levers *G'* being pivoted to the 110 upright frame at the top, substantially as specified.

FITZALLAN B. WILLIAMS.
